United States Patent

Des. 240,627
Patented July 20, 1976

240,627

COMBINATION LAVATORY, TOILET AND URINAL

Earl L. Morris, Whittier, Calif., assignor to Acorn
Engineering, City of Industry, Calif.

Filed Mar. 10, 1975, Ser. No. 557,023

Term of patent 14 years

Int. Cl. D23—02

U.S. Cl. D23—49

FIG. 1

FIG. 2

FIG. 3

FIG. 4

FIG. 1 is a perspective view of a combination lavatory, toilet and urinal showing my new design;

FIG. 2 is a top plan view thereof;

FIG. 3 is a left side elevational view thereof; and

FIG. 4 is a right side elevational view thereof.

I claim:

The ornamental design of a combination lavatory, toilet and urinal, as shown.
